UNITED STATES PATENT OFFICE.

HOWARD G. ALLEN, OF NIAGARA FALLS, NEW YORK, ASSIGNOR TO THE J. L. MORRISON COMPANY, INC., OF NIAGARA FALLS, NEW YORK, A CORPORATION OF NEW YORK.

GAUGE MECHANISM FOR STAPLING MACHINES.

Application filed April 9, 1924. Serial No. 705,369.

This invention relates to a gauge mechanism for wire stapling or stitching machines and has for its objects the production of a gauge mechanism for machines of this character which permits of stitching boxes at the corners thereof and which can be readily adapted to definitely locating either one stitch, or two stitches, and also permit of applying extra stitches between two definitely spaced stitches, and which can be readily adjusted for stitching boxes of different sizes.

In the accompanying drawings:—

Figure 1 is a fragmentary perspective view of a stapling machine for staying the corners of boxes equipped with my improved gauge mechanism. Figure 2 is a side elevation of the same with a box shown in section and in position for applying the front staple to the corner thereof. Figure 3 is a vertical cross section taken on line 3—3, Fig. 2. Figure 4 is a fragmentary vertical longitudinal section taken on line 4—4, Fig. 2, and showing one way of determining the limits of the longitudinal movement of the gauge mechanism. Figures 5 and 6 are similar views showing another way of controlling the movement of the gauge member. Figure 7 is a cross section taken on the correspondingly numbered line in Fig. 2. Figure 8 is a longitudinal section taken on line 8—8, Fig. 4, on an enlarged scale.

Similar characters of reference indicate like parts throughout the several views.

The stapling or stitching mechanism shown in the drawings, as an example of the machine on which my improved gauge mechanism is capable of being used, comprises a standard 10, a supporting arm 11 projecting forwardly from said standard, a clincher box 12 mounted on the front end of said arm and containing the mechanism whereby the staple driven through the box is clinched on its under side, a supporting head 13 arranged above the supporting arm, and a staple forming and driving mechanism 14 mounted on the head above the clincher box and adapted to form staples from a supply of wire and drive the same through the box from the outer side of the same.

The upper side of the clincher box and the supporting arm are constructed upwardly pointing V-form in cross section so as to form a seat or saddle of this shape on which the corner of a box to be stayed or

stapled is adapted to rest. This box for example may consist of four walls 15 forming a rectangular enclosure and a bottom 16 connected with the lower ends of the side walls.

The gauge mechanism associated with this stapling mechanism and containing my invention is constructed as follows:

Two longitudinal side bars are arranged lengthwise along the lower parts of the opposite inclined sides of the saddle or seat formed by the clincher box and supporting arm. Each of these bars is preferably constructed of angular form in cross section and has one of its outer or upper flanges 18 arranged parallel with the respective side of the saddle and sliding therein and its inner or lower flange 19 projecting downwardly from the upper edge of the upper flange and sliding in a longitudinal groove 20 in the adjacent part of the supporting arm. Mounted on the front ends of the sliding bars is a front transverse plate 21 which is of rectangular form and arranged with two of its sides converging upwardly to a point and arranged parallel with the upwardly converging sides of the clincher box and the supporting arm.

The rear ends of the side bars are connected by an upwardly pointing V-shaped cross piece 22 which extends over the rear part of the supporting bar and has its sides parallel therewith.

The side bars, front plate and rear cross piece, in effect form a carrier, frame or rack which is slidable horizontally forwardly and backwardly on the supporting arm.

Upon this carrier or frame is mounted a gauge which is preferably constructed in the form of a wing 23 having a recess 24 in its upper central part which receives the supporting arm and permits of extending the lower part of the wing transversely underneath the supporting arm and extending its opposite end portions upwardly along opposite sides of said arm, as shown in Fig. 3. This gauge may be detachably connected with the side bars so as to be capable of longitudinal adjustment thereon by any suitable means, those shown in Figures 2 and 3 being preferred and consisting of two brackets 25 secured to the rear side of the upwardly projecting end portions of the gauge wing and overlapping the adjacent parts of the sliding bars, two clamping plates 26 each arranged with its outer end below one of the

brackets 25 and engaging its upper end with the underside of the upper flange of the adjacent sliding bar, as shown in Fig. 3, a dowel 27 connecting the lower end of each 5 clamping plate and the adjacent part of the respective bracket, and a clamping screw 28 connecting the central part of each clamping plate and the adjacent bracket. By this means the gauge wing can be readily and 10 easily adjusted lengthwise on the sliding frame to suit different heights of boxes which are to be stayed and it also permits of quickly and conveniently changing one gauge plate for another of a different size 15 to suit the diameter of the boxes which are being stayed by means of staples.

Means are provided for controlling the position of the gauge frame on the supporting arm and retaining the same in a fixed 20 position thereon, also permitting the same to reciprocate lengthwise, and also to provide adjustable stops for limiting the forward and backward movement of the sliding frame and gauge wing at predetermined 25 points to suit the location where it is desired to apply the staples to the corners of the boxes.

In the preferred form the means for thus controlling the position of the sliding frame 30 are constructed as follows:

The numeral 29 represents a clip secured to one part of the cross piece of the sliding frame by means of a screw 30 and provided with a depending tappet 31 which moves 35 lengthwise in a longitudinal groove 32 formed in the top of one of the sloping sides of the supporting arm. This tappet may either be engaged on its front and rear sides by front and rear stop blocks 33, 34, secured 40 in the groove 32 for holding the gauge frame against longitudinal movement or these stop blocks may be secured in this groove at a distance from each other and thus permit the gauge frame to have a limited longitudinal 45 movement by engagement of the tappet alternately with these stop blocks. For this purpose clamping screws 35 are provided which pass through the stop blocks and are adapted to engage one or another pair of 50 threaded openings 36 arranged in a longitudinal row in the bottom of the groove.

For the purpose of accurately locating the 55 places where the gauge wing comes to rest at the front and rear ends of its longitudinal movement and also to permit of a certain degree of refinement in adjusting these stopping places to enable the staples to be located at or substantially at the desired places on the boxes the openings 36 in the 60 supporting arms are spaced equidistant, say one-half inch apart, and each stop block is made of a definite length, say seven-eighths of an inch, and provided with two openings 37, 38 which are spaced apart, say one-quarter inch, and arranged different dis-

tances from opposite ends of the respective block, say the opening 37 is arranged one-quarter inch from one end of the stop block and the other opening three-eighths of an inch from the other end of this block. It 70 follows from this construction that a coarse adjustment of each block can be effected on the supporting arm by shifting the screw 35 from one arm opening 36 to another which permits of half inch stops. By securing the stop block with the screw passing through the short end of the respective block and presenting the long end of the same to the tappet the gauge frame will be arrested five-eighths of an inch from the respective 80 arm opening as shown in Figures 5 and 8. If it is now desired to obtain a finer adjustment this can be accomplished by shifting the screw from the near opening 37 to the far opening 38 as shown in Figure 4, thereby shifting the block toward the respective securing opening in the arm to the extent of one quarter of an inch so that now that long end of the stop is only three-eighths of an inch from the securing opening in the arm. Upon reversing the stop block end for end and securing the same by passing the screw 35 through either the rear opening 37 in the short end thereof or through the far opening 38 in the long end thereof the tappet 90 may arrest either one-quarter inch or one-half of an inch from the respective screw opening 36 in the supporting arm. These means permit a comparatively fine adjustment, say down to one-eighth of an inch, to 100 be obtained for arresting the gauge frame in its forward and backward movement to suit the desired location of the staples on the box by the use of only two stop blocks.

The tappet is preferably made of a thickness equal to the finest adjustment possible, in this case one-eighth of an inch, which permits both stop blocks to be secured to the supporting arm with the tappet confined between them against movement in either direction as shown in Fig. 6, thereby permitting the stop blocks to also serve for holding the gauge frame immovably in one position when only one staple is to be applied in a certain place on the box. When the gauge frame is movably mounted on the supporting arm the same is yieldingly held in its forward position with its tappet engaging with the front stop block by means of a spring 39 connecting the cross piece of the sliding gauge frame with the supporting head of the staple forming and driving mechanism. This spring is sufficiently strong to hold the gauge carrier or frame and its gauge wing sufficiently rigid in a forward position to permit the operator to gauge the box against the front side of the gauge wing and the front plate by the ordinary movements of the hand but will readily yield when the operator exerts a delib- 115 120 125 130

erate pressure at will backwardly against the box on the sliding frame.

The operation of stapling boxes by this gauging mechanism is as follows:

- 5 Preparatory to operating the machine a gauge wing of dimensions suitable for the diameter of the box to be stapled is selected and mounted on the carrier or sliding frame at a distance from the front transverse plate 10 equal to the depth or height of the box. The front stop block is now secured to the supporting arm in such a position that the forward movement of the carrier will be arrested when that part of the box corner intended 15 to receive the uppermost or front staple is vertically in line with the staple forming, driving and clinching mechanism, and the rear stop is so located on the supporting arm that the rearward movement of 20 the carrier will be arrested when that part of the box corner intended to receive the lowermost or rear staple is vertically in line with the staple forming, driving and clinching mechanism. After such adjustments 25 have been made the carrier when free will be moved forwardly and held yieldingly in its foremost position by the shifting spring. The operator now places a box with its 30 opened end over the carrier and the front end of the supporting arm and with the front edge of its walls engaging the gauge wing and its bottom engaging the transverse front plate. The spring is sufficiently stiff so that when the box is pressed lightly 35 against the gauge wing and front plate of the carrier the spring will offer enough resistance so that this gauge wing and plate are practically immovable at this time. While the carrier is in this position the box 40 gauged therein presents the foremost part of its corner to the stapling mechanism so that a staple may be applied thereto. Upon applying sufficient backward pressure against the box and carrier to overcome the resistance 45 of the spring the carrier and box can be pushed backwardly until the same are arrested by the rear stop and thereby presenting the rearmost part of the box corner to the stapling mechanism for applying a staple thereto. If the box corner is to be 50 stapled at one or more places between the front and rear stapling places the carrier can be manipulated manually for bringing the box corner to the desired places at any time that 55 the operator chooses.

It will thus be clear that the position of the front and rear staple is definitely determined by the front and rear stops but that the position of the intermediate staple or 60 staples is indeterminate and depends upon the skill of the operator for locating them properly. When the stapling is completed and the operator removes the back pressure against the carrier the same is returned to 65 its foremost position by the spring.

If the box is to receive only one staple the gauge frame or carrier can be rigidly held on the supporting arm by so fastening the end stops to the supporting arm that the tappet is confined against longitudinal 70 movement therebetween, thus bringing each box when placed on the gauge frame in the proper position to receive the staple at the place desired.

Owing to the facility with which the boxes 75 can be gauged in the different positions where the same are intended to receive staples and the means for definitely locating the extreme staples it is possible to effect such work rapidly and easily and to obtain an 80 cut-put without undue strain or attention on the part of the operator thereby expediting work and rendering the same easier and also enabling the cost of production to be materially lowered, as well as ensuring uniformity and superiority in the work.

I claim as my invention:—

1. A gauge mechanism for a box stapling machine having a stapling mechanism and a supporting arm upon which the box is 90 supported while being stapled, comprising a carrier movable lengthwise on said arm and having a transverse bearing surface at its front end which is adapted to be engaged by the bottom of the box and a transverse 95 gauge member in rear of said bearing surface which is adapted to be engaged by the upper edge of the box.

2. A gauge mechanism for a box stapling machine having a stapling mechanism and a supporting arm provided on its opposite sides with longitudinal grooves, comprising a box carrier having two longitudinal bars each having a depending flange sliding lengthwise in one of said grooves, a cross 100 piece connecting the rear ends of said bars, a transverse plate connecting the front ends of said bars and adapted to be engaged by the bottom of the box, and a transverse gauge 105 member mounted on said bars in rear of said front plate and adapted to be engaged by the upper edge of the box.

3. A gauge mechanism for a box stapling machine having a stapling mechanism and a supporting arm provided on its opposite 110 sides with longitudinal grooves, comprising a box carrier having two longitudinal bars each having a depending flange sliding lengthwise in one of said grooves, a cross piece connecting the rear ends of said bars, a transverse plate connecting the front ends 115 of said bars and adapted to be engaged by the bottom of the box, a transverse gauge wing arranged in rear of said front plate and adapted to be engaged by the upper edge 120 of the box, and means for adjustably connecting said wing with said bars consisting of two brackets arranged on said wing and adapted to engage the upper sides of 125 said bars, clamping plates each engaging its 130

inner end with the underside of one of said bars, dowel pins each arranged in the outer end of a clamping plate and the adjacent bracket, and clamping bolts each connecting the central part of one clamping plate with the adjacent part of the respective bracket.

4. A gauge mechanism for a box stapling machine having a stapling mechanism and a supporting arm provided with a longitudinal groove, comprising a box carrier movable lengthwise on said arm, a tappet mounted on said carrier, and front and rear stop blocks arranged in said groove and adjustable lengthwise therein and adapted to be engaged by said tappet for limiting the forward and backward movement of said carrier.

5. A gauge mechanism for a box stapling machine having a stapling mechanism and a supporting arm provided with a longitudinal groove and a longitudinal row of threaded openings in said groove, comprising a box carrier movable lengthwise on said arm, a tappet mounted on said carrier, front and rear stop blocks arranged in said groove and adjustable lengthwise therein and adapted to be engaged by said tappet for limiting the forward and backward movement of said carrier, and fastening screws arranged in said blocks and adapted to engage different ones of said threaded openings.

6. A gauge mechanism for a box stapling machine having a stapling mechanism and a supporting arm provided with a longitudinal groove and a longitudinal row of threaded openings in said groove, comprising a box carrier movable lengthwise on said arm, a tappet mounted on said carrier, front and rear stop blocks arranged in said groove and adjustable lengthwise therein and adapted to be engaged by said tappet for limiting the forward and backward movement of said carrier, and fastening screws arranged in said blocks and adapted to engage different ones of said threaded openings, each of said blocks having a plurality of openings arranged different distances from opposite ends of the same and adapted to receive the respective fastening screw.

7. A gauge mechanism for a box stapling

machine having a stapling mechanism and a supporting arm provided with a longitudinal groove and a longitudinal row of threaded openings in said groove, comprising a box carrier movable lengthwise on said arm, a tappet mounted on said carrier, front and rear stop blocks arranged in said groove and adjustable lengthwise therein and adapted to be engaged by said tappet for limiting the forward and backward movement of said carrier, and fastening screws arranged in said blocks and adapted to engage different ones of said threaded openings, each of said blocks adapted to be reversed so that either of its ends forms a stop surface.

8. A gauge mechanism for a box stapling machine having a stapling mechanism and a supporting arm provided with a longitudinal groove and a longitudinal row of threaded openings in said groove, comprising a box carrier movable lengthwise on said arm, a tappet mounted on said carrier, front and rear stop blocks arranged in said groove and adjustable lengthwise therein and adapted to be engaged by said tappet for limiting the forward and backward movement of said carrier, and fastening screws arranged in said blocks and adapted to engage different ones of said threaded openings, each of said blocks adapted to be reversed so that either of its ends forms a stop surface and each of said blocks having openings arranged different distances from opposite ends thereof and adapted to receive the respective fastening screw.

9. A gauge mechanism for a box stapling machine having a stapling mechanism and a supporting arm provided with a longitudinal groove, comprising a box carrier movable lengthwise on said arm, a tappet mounted on said carrier, and front and rear stop blocks arranged in said groove and adjustable lengthwise therein and adapted to be engaged by said tappet for limiting the forward and backward movement of said carrier and a spring connecting said carrier with a relatively stationary part of the machine and operating to hold the carrier yieldingly in its forward position.

In testimony whereof I affix my signature.

HOWARD G. ALLEN.
